UNITED STATES PATENT OFFICE.

EDWARD FOOSE, OF ROCKVILLE, MARYLAND.

DESIGN FOR A RADIOANTENNA.

Application filed March 9, 1926. Serial No. 16,846. Term of patent 14 years.

To all whom it may concern:

Be it known that I, EDWARD FOOSE, a citizen of the United States, residing at Rockville, in the county of Montgomery, State of Maryland, have invented a new, original, and ornamental Design for a Radioantenna, of which the following is a specification, reference being had to the accompanying drawing, forming a part thereof.

Figure 1 is a side elevation of an antenna embodying my new design, and

Fig. 2 is an edge elevation thereof.

I claim:

The ornamental design for a radioantenna, as shown.

EDWARD FOOSE.
